UNITED STATES PATENT OFFICE.

HENRY B. COBB, OF WILMINGTON, DELAWARE.

WIRE-CABLE MACHINE.

SPECIFICATION forming part of Letters Patent No. 452,517, dated May 19, 1891.

Application filed May 29, 1890. Serial No. 353,560. (No model.)

To all whom it may concern:

Be it known that I, HENRY B. COBB, a citizen of the United States, residing at Wilmington, in the county of New Castle and State of Delaware, have invented a new and useful Improvement in Wire-Cable Machines, of which the following is a specification.

The object of my invention is to provide an improved machine for the purpose of twisting wires together to form thereof cables, particularly for conducting electric currents.

My invention consists in the general construction of my improvement; and it also consists in details of construction and combinations of parts.

In the accompanying drawings, Figure 1 is a broken sectional plan view of a cable-making machine provided with my improvements; Fig. 2, a view showing means for transmitting the driving-power of the machine to the reel upon which the cable is wound as it is made, and Fig. 3 a section taken at the line 3 3 of Fig. 1 and viewed in the direction of the arrows.

A is the frame of the machine, formed of any suitable material, and preferably of the rectangular shape illustrated, being strengthened at intervals by braces B, through which passes a tubular rotary shaft C, supported toward its rear end in suitable bearings *t* and *t'* and toward its forward end by a rotary guide-block *f*, hereinafter referred to, in a bearing *f'*, the first-named of which bearing is provided on an extension A' at the rear end of the frame A, and at each brace (or at each of so many of the braces as there are provided spool-carriers, hereinafter described) surrounding the shaft C is a short stationary sleeve *r*, which should be encircled at intervals by separate guide-grooves *q*, the number of which on each sleeve should correspond with the number of spools on each spool-carrier, as and for a purpose hereinafter explained. A sleeve *r'* is provided on the rear end of the frame A, and between each sleeve *r* and the shaft C is an annular space *s*, the provision thereof forming the only material difference between the sleeves *r* and *r'*, the latter not requiring the annular space *s*.

D is the core-tube extending through the hollow shaft C, being secured therein against rotation, as by means of the pin *x*, inserted

into it through the bearing *x'* for its rear end, and provided at its forward projecting end with a nipple *D'*, removably secured in place, as shown, whereby it may readily be supplanted by others having their openings in diameter suitable to admit through them cores of different thicknesses. From the forward end of the frame A extends a bracket *p*, supporting a guide-eye *p'* for the cable as it is formed, and whence it is led to the reel E, the eye *p'* being axially coincident with the opening in the nipple *D'*, between which and the eye the twisting of the wires about the core-wire takes place.

F, Fig. 3, is a spool-carrier or rotary head, which I prefer to form as a hub *o*, secured to the shaft C to rotate with it, and preferably abutting against a sleeve *r*, and having arms *n* extending radially from it in desired number, according to the number of spools *h* (hereinafter described) it is intended to carry, though my improvement is not intended to be limited to this particular form of the head F. Near the outer end of each arm *n* is a bearing *m* for a rotary spindle *l*, extending transversely of its supporting-arm, being confined in its position and provided at one projecting end with a pulley *k*, secured upon it to revolve with it, and at its opposite projecting end with a frame *i*, having journaled in its opposite sides a spool *h* for the wire to be laid up into the cable. As many of the heads F may be provided on the shaft C as the dimensions of the machine (which may be of any desired size) will accommodate, and all or any number thereof may be used at once, though, as shown, the intention is to provide for their successive use by stringing the wire from the spools in the manner indicated by dotted lines in Fig. 1, and which stringing operation is hereinafter more definitely referred to.

As shown in Fig. 3, the rotary head F (all the heads are alike) is provided with seven spools *h*, and, accordingly, is formed with seven radial arms, each carrying a rotary spindle *l*, with its pulley *k* and frame *i*. It will be noticed on reference to Fig. 1 that the spindles *l* there shown project at the ends carrying the pulleys *k* at varying lengths from their bearings, and this is true of each of the (seven) spindles on each head F, in order

- that the pulley thereon may coincide, or at least approximately coincide, with a different plane on the stationary sleeve or bearing r or r' adjacent to the head, with which the pulley is connected by an endless band g , passed around it and the sleeve, on which latter it is preferred to provide a guide-groove for each band in line with the pulley thereby controlled.
- 10 o The shaft C may be driven by connecting it with the driving-power through a belt-pulley II, and from the rotary shaft C, I operate the reel E through the media of the gear-wheel w on the said shaft meshing with a similar wheel w' on a counter-shaft w^2 , supported in bearings at a side of the frame A and carrying at its farther end a beveled gear v , (see Fig. 2,) meshing with a similar gear v' on a rotary shaft v^2 , carrying a belt-pulley v^3 , connected by a belt u , with a pulley u' , like the pulley v^3 on the shaft u^2 of the reel E.
- The operation is as follows: The wires on the spools h (or any desired number of them) of a head F (say the first) are strung by passing them, respectively, through the ends of the frames i and thence through a perforated rotary guide-block f near the forward end of the shaft C, through the eye p' , where they are brought together with the core-wire d , which is strung through the tube D and nipple D' , and all the wires are thence led to the reel E. The shaft C is then rotated and all the wires from the said spools twisted around the wire d between the nipple D' and eye p' , being wound on the reel in the form of a cable thus produced by the twisting. It will be noticed that the head F and frames i , carrying the spools, rotate on the axis of the head, and that each spool by the unwinding of the wire from it is rotated on its axis in a direction at a right angle to the rotation of the head. Were no means provided to prevent, these two directions of rotation would obviously produce twisting of the fiber of the wire, with the consequent well-known injury thereto. To prevent this result, the frames i are caused to rotate on their respective axes in the opposite direction from that of the rotation of the shaft C, and the means I provide for producing their described rotation—namely, the bands g , connecting the pulleys k with respectively coinciding planes on the sleeve-bearings r r' —are simple and effective for their purpose. If, as shown, the heads F are intended to be used successively, as soon as the wires on the first have been exhausted, on stopping the machine, those on the next may be strung by leading them from the spools through the annular opening within the adjacent sleeve r and openings in the adjacent hub o and the rotary block f to the core, which may then comprise the cable formed by the previously-twisted wires and previously strung through the tube D. In the same manner all the heads F may be brought successively into operation, the wires being strung in each instance through all the

sleeves r r' and perforated hubs o in advance of the respective heads, the cable previously formed being intended to be used in each instance as the core, though of course it is not necessary that it should. However, such is my practice where a cable is formed consisting of a large number of twisted wires. Thus a core with its successive increments may repeatedly be passed through the core-tube and attached nipple, and, as hereinbefore suggested, nipples of correspondingly varying bores would then be used successively as the cable acquired increased proportions. It is also quite feasible with a machine of my improved construction, to have all or any number of the heads F in operation at the same time, provision then being of course made for stringing the wires through the sleeves r r' and hubs o in advance of the respective heads, and thus by a single operation of the machine a cable may be produced of twisted wires equaling in number the product of the number of spools h multiplied by the number of heads F used in the operation.

What I claim as new, and desire to secure by Letters Patent, is—

1. In a cable-making machine, the combination, with the frame A, of a rotary hollow shaft C, containing a stationary core-tube D and carrying a head F, a stationary bearing r or r' , surrounding the shaft, frames i on rotary spindles l on the head and adapted to carry spools, and pulleys k , coinciding, respectively, and connected by bands g with different planes on the said bearing, substantially as and for the purpose set forth.
2. In a cable-making machine, the combination, with the frame A, of a rotary hollow shaft C, containing a stationary core-tube D, provided with a nipple D' , removably secured on its forward end, a head F on the rotary shaft, a stationary bearing r or r' , surrounding the shaft, frames i on rotary spindles l on the head and adapted to carry spools, pulleys k , coinciding, respectively, and connected by bands g with different planes on the said bearing, and the bracket p , provided with an eye p' , supported to coincide axially with the nipple D' , substantially as and for the purpose set forth.
3. In a cable-making machine, the combination, with the frame A, of a rotary shaft C, heads F, secured at intervals to the shaft and having rotary spindles l , carrying frames i , adapted to carry spools h , pulleys k , supported on the spindles of each head at varying distances from their bearings, a stationary sleeve-bearing r or r' , surrounding the shaft adjacent to each head, and bands g , connecting the pulleys k of each said head, respectively, with an adjacent bearing on different planes thereof, substantially as and for the purpose set forth.
4. In a cable-making machine, the combination, with the frame A, of a rotary hollow shaft C, containing a stationary hollow core-

13
tube provided at its forward end with a removably-adjustable nipple D', a bracket p, provided with an eye p', supported to coincide axially with the nipple, heads F, supported at 5 intervals on the shaft, each head comprising radial arms n on a longitudinally-perforated hub o, spindles k, journaled in the ends of the arms and carrying frames i, adapted to support spools h and provided at their rear ends 10 with pulleys k, extending on each head at varying distances from the spindle-bearings, a

perforated block f on the shaft, and circumferentially-grooved stationary sleeve-bearings r r', surrounding the shaft C near the hubs of the heads F, the whole being constructed and arranged to operate substantially as 15 described.

HENRY B. COBB.
